(57) **CLAIM**

The ornamental design for a dog leash assembly for use with a bicycle, as shown and described.

DESCRIPTION

FIG. 1 is a top, front, right perspective view of a dog leash assembly for use with a bicycle, showing our new design; FIG. 2 is a front elevation view thereof; FIG. 3 is a rear elevation view thereof; FIG. 4 is a right side elevation view thereof; FIG. 5 is a left side elevation view thereof; FIG. 6 is a top plan view thereof; FIG. 7 is a bottom plan view thereof; and, FIG. 8 is a top, front, right perspective view of the dog leash assembly for use with a bicycle, shown in a condition of use. In the drawings, the broken line showing of a leash, fasteners, and leash hardware depicts portions of the dog leash assembly for use with a bicycle that forms no part of the claimed design. In FIG. 8, the broken line showing of a human, dog, and bicycle depicts environmental subject matter only and forms no part of the claimed design.
